UNITED STATES PATENT OFFICE.

AUGUSTUS D. COOK, JR., OF LAWRENCEBURG, INDIANA.

DOUBLE-ACTING OIL AND WATER PUMP.

Application filed May 14, 1923. Serial No. 638,818.

To all whom it may concern:

Be it known that I, Augustus D. Cook, Jr., a citizen of the United States, residing at Lawrenceburg, in the county of Dearborn and State of Indiana, have invented certain new and useful Improvements in Double-Acting Oil and Water Pumps, of which the following is a specification.

The object of my invention is to provide simple, efficient, convenient and easily operated means for locating, anchoring and releasing a division stuffing box in a deep well.

My invention consists in the construction, combination and arrangement of parts as herein set forth and claimed.

In the drawings:

Fig. 1 is a view partly in vertical section and partly in elevation showing a section 20 of a tubular well cylinder containing the division housing with the stuffing box in anchored position therein, the plunger rod, plungers and part of the division housing and stuffing box being shown in elevation;

Fig. 2 is a plan view enlarged of the anchoring unit on the line 2—2 of Fig. 7, the division housing being shown in transverse section;

Fig. 3 is a side elevation of the anchoring 30 unit;

Fig. 4 is a plan view of the division housing;

Fig. 5 is a side elevation of the division housing;

Fig. 6 is a bottom view thereof;

Fig. 7 is an enlarged vertical section partly in elevation showing the stuffing box in anchored position in the division housing;

Fig. 8 is a perspective view of the anchoring unit and stuffing box;

Fig. 9 is a perspective view of one of the anchoring dogs; and

Fig. 10 is a partial sectional and plan view showing the anchoring dogs in released position.

In order to illustrate a preferred embodiment of my invention I have shown a working barrel comprising an outer tube or cylinder 1 connected at its top to tubular coupling 2 and at its bottom to tubular coupling 3, and an inner sectional tube 4 connected at its top to tubular coupling 2 and having its lower end 5 tapered and adapted to project and wedge into tapered packing 6 in coupling 3. Inner tube 4 is

provided near its top with ports 4' and near its bottom with ports 4''. Said inner tube 4 is formed in two sections between which division housing 7 is interposed. Said division housing is externally screw threaded adjacent its upper end and is screwed into the upper section of inner tube 4, forming shoulder 8 therein. Division housing 7 is internally screw threaded adjacent its lower end and the upper end of the lower section of tube 4 is screwed therein.

Division housing 7 comprises a cylindrical tube having the same interior diameter as the lower section of inner tube 4. It has 70 a semi-circular outwardly extending flange 9 at its top on one side and a similar flange 10 at its bottom on the outer side, said flanges being connected by vertical ribs 11 and 12 and said flanges and ribs forming a 75 division in the space between tubes 1 and 4. Said division housing is provided upon one side near its top with ports 13 and on the other side near its bottom with ports 14. Near the longitudinal center of said division housing and intermediate of said ports I provide an interior circumferential channel 15. Inner tube 4 is provided in its lower end with a suitable foot valve 16 which has 80 wedging engagement therein.

Division stuffing box 17 comprises ring 18 having inner tapering wall 19 and cut-away on its outer periphery to form space 20 to receive cup-leather 21. Said ring and cup-leather are provided with vertical bolt 90 holes 22 and 23, respectively. Mounted above said cup-leather and ring I provide tubular stem 24 having outwardly extending flange 25 provided with threaded holes 26 adapted to register with bolt holes 22 95 and 23 in said cup-leather and ring, respectively. The inner wall 19' of the lower end of tubular stem 24 is beveled or flared outwardly to coincide with tapering wall 19 and the upper inner wall of said tubular stem is cut away to form packing space 27 in which is inserted cup-leather 28, flanged spacing sleeve 29, cup-leather 30 and retaining ring 31 screwed therein. Tubular stem 24 is provided upon its upper end with cylindrical web 24' integrally formed thereon and having the lower side of its periphery adapted to rest on shoulder 8 to limit the downward movement of the stuffing box and to support it within division housing 7.

My novel anchoring unit comprises hol-

low disk 32 of slightly smaller diameter than the inner wall of inner tube 4 and is provided with a plurality of vertical bolt holes 33 receiving bolts 34 adapted to register with bolt holes 22, 23 and 26. Anchoring dogs 35 each having curved outer end 35' and inner end 35" are pivotally mounted on bolts 34 extending upwardly through the bolt holes in hollow disk 32, ring 18, cup-leather 21 and flange 25 in which latter said bolts are screwed into holding engagement. A coil expansion spring 38 encircling each bolt 34 in recess 36 of dogs 35 and attached at one end to hollow disk 32 and at the other end to dog 35 serves to normally hold the ends 35' of said dogs in engagement with the walls of said division housing, including channel 15 and the upper shoulder thereof and at the same time to hold the ends 35" in engagement with plunger rod 37.

The lower plunger 39 is mounted in inner tube 4 between foot valve 16 and division housing 7 and is provided with tapering shank 40 forming the lower end of plunger rod 37. Upper plunger 41 is mounted on said plunger rod a short distance above division housing 7.

My invention is adapted to be installed in deep wells having walls of varying types but the ordinary construction consists of a well having a tubular metal casing or wall and provided at its lower end with a tubular strainer through which the oil or water filters into the well.

When installing the apparatus embodying my invention into the well casing the lower end of drop pipe or suction tube 42 is screwed into coupling 2 of said working barrel and the working barrel is lowered by adding sections of drop pipe until said working barrel rests in the bottom of the well. The foot valve or bottom check 16 is then lowered into position, as shown in Fig. 1, by suitable tools. The lower plunger, division stuffing box, connecting rod and upper plunger are assembled and lowered through the well casing down into operative position in the working barrel, as shown in Fig. 1. When in this position web 24' of the division stuffing box rests upon shoulder 8 of division housing 7 and said stuffing box is automatically anchored in said division housing by dogs 35 engaging upper shoulder 15' of circular channel 15.

Plunger rod 37 is of uniform diameter for some distance below the anchoring unit or mechanism A to permit it to freely reciprocate up and down during the pumping operation but is provided with a taper 40 above lower plunger 39 so that when it is desired to remove the interior mechanism for repairs or for other purposes it is only necessary to pull plunger rod 37 upwardly

whereupon taper 40 will automatically engage the inner ends 35" of dogs 35 and force ends 35' out of engagement with circular channel 15 thereby releasing anchoring unit, division stuffing box, plungers and plunger rod for withdrawal from the well. When placing said mechanism in the well the anchoring dogs will automatically engage upper shoulder 15' of channel 15 and prevent upward movement while the lower surface of web 24' will rest upon the top of shoulder 8 and prevent further downward movement, thereby securely holding the stuffing box in fixed position in the division housing during the operation of pumping and at all other times except when plunger rod 37 is pulled upwardly out of pumping position for withdrawal of the mechanism.

While I have shown my invention as applied to a double plunger one way work stroke, it may also be used in connection with various other types of operative mechanisms, such as double stroke type cylinder, one that requires the same amount of power on the up stroke as on the down stroke and also a two or three stroke type cylinder, that is one using two or three sets of separate driving rods or lifting rods.

While I have shown and described a particular construction and arrangement of parts it will be understood that various modifications may be made without departing from the scope or spirit of the invention as defined in the claims.

What I claim as new and desire to secure by Letters Patent is:

1. In a device of the class described, a tube having a working barrel therein provided with a shoulder and circumferential channel, a division stuffing box, an anchoring unit connected to said division stuffing box and comprising a hollow disk and a plurality of pivotally mounted dogs adapted to normally press outwardly against the wall of said tube and engage the wall of said channel, a plunger rod, plungers carried by said plunger rod, and said plunger rod having a tapered section adapted when drawn upwardly to engage the arms of said dogs whereby they are moved upon their pivots out of holding engagement with said tube.

2. In a device of the class described, a working barrel having an inner sectional tube, a division housing interposed between the sections of said tube and having a locating shoulder on its upper end and a circular channel therebelow, a plunger rod, plungers carried thereby, a division stuffing box on said plunger rod between said plungers and means carried by said division stuffing box for automatically anchoring and releasing said stuffing box and operative mechanism.

3. In a device of the class described, a

working barrel having a division stuffing box therein provided with a shoulder and circular channel, an anchoring unit connected to said division stuffing box and comprising a hollow disk and a plurality of pivotally mounted dogs adapted to press outwardly against the wall of said working barrel and adapted to engage the wall of said channel.

4. In a device of the class described, a tube, a working barrel connected thereto, a plunger rod tapering upwardly a portion of its length, a plunger on said plunger rod, a stuffing box on said plunger rod within said working barrel and having an upwardly tapering inner wall adapted to cooperate with the upwardly tapering portion of said plunger rod, and means on said stuffing box and said working barrel, respectively, for automatically anchoring said stuffing box to said working barrel.

5. In a device of the class described, a tube, a working barrel connected thereto and provided with a circumferential channel and shoulder, a division stuffing box, an anchoring unit connected to said division stuffing box and comprising a disk, a plurality of dogs pivotally mounted on said disk and adapted to normally press outwardly against the inner wall of said working barrel and engage the wall of said channel, a plunger rod, plungers carried by said plunger rod, said plunger rod having a tapered section adapted when drawn upwardly to engage the arms of said dogs whereby they are moved upon their pivots out of holding engagement with said tube and a spring connected to each dog adapted to normally and

automatically throw the dog into said channel and into holding engagement with said shoulder.

6. In a device of the class described, a working barrel having a circumferential channel and shoulder, a stuffing box slidably mounted within said working barrel and having an upwardly tapering inner wall, an anchoring unit connected to said stuffing box and having pivotally mounted anchoring dogs thereon each provided with an arm having a curved end adapted to engage said plunger rod and the wall of said channel, respectively, for the purposes set forth.

7. In a device of the character described, a working barrel having a circumferential channel and shoulder, a stuffing box slidably mounted within said working barrel and having an upwardly tapering inner wall, an anchoring unit connected to said stuffing box and having pivotally mounted anchoring dogs thereon each provided with an arm adapted to engage said plunger rod and a coil spring engaging each of said dogs whereby said dogs are adapted to engage the wall of said channel, for the purposes specified.

8. In a device of the character described, a working barrel, a plunger rod, a stuffing box on said plunger rod and slidably mounted within said working barrel, an anchoring unit connected to said stuffing box and having pivotally mounted anchoring dogs thereon, each provided with an arm adapted to be engaged by said plunger rod whereby said dogs disengage the inner wall of said working barrel, for the purposes specified.

AUGUSTUS D. COOK, JR.
